UNITED STATES PATENT OFFICE.

CHARLES M. CONKLIN, OF CINCINNATI, OHIO.

SPARK-PLUG.

1,093,113.

Specification of Letters Patent. Patented Apr. 14, 1914.

Application filed November 6, 1909. Serial No. 526,507.

To all whom it may concern:

Be it known that I, CHARLES M. CONKLIN, a citizen of the United States of America, and resident of Cincinnati, Hamilton county, 5 State of Ohio, have invented certain new and useful Improvements in Spark-Plugs, of which the following is a specification.

This invention relates to spark plugs and has for an object to produce an improved 10 plug which overcomes difficulties encountered with the existing plugs known to me.

A difficulty encountered with existing plugs is that the insulating core located between the shell portion of the plug and the 15 central terminal post or electrode is subjected to the high temperature of the engine cylinder, and to the comparatively low temperature which exists outside of the cylinder. This construction results in temperature strains, which cause a tendency 20 of the core to break, and, consequently, if there is an inherent defect or weakness in the core it will break. I overcome this difficulty by providing an insulating core, preferably 25 of porcelain, which is made in two parts, one of which is subjected to the heat of the engine cylinder, and the other of which is exposed to the temperature exterior to the cylinder. I also provide a non-conducting 30 and heat insulating diaphragm between the two parts, to protect the outer part from the heat of the engine cylinder, and to prevent an interchange of temperatures between the two parts. Another difficulty encountered 35 with plugs of the jump-spark type, is that the spark points or terminals become ineffective and render the inner plug useless. The spark points or terminals are rigidly secured in place, so that they can only be 40 removed and replaced by a skilled mechanic and with considerable labor. I overcome this difficulty by providing spark points which are removably mounted on the plug, and which may be easily removed and replaced.

It is extremely difficult to remove and replace the insulating core of all plugs known to me, when the plug becomes fouled or short circuited by the depositions of soot or carbon 45 on the core. This difficulty is encountered because the joints between the shell and the core, and between the central electrode or terminal post and the core must be carefully packed. I overcome this by so constructing 50 the inner part of the porcelain core that it

may be removed and replaced without disturbing the necessary packings.

In the drawings accompanying this application and forming a part thereof, Figure 1 is a vertical section of a spark plug embodying my invention. Fig. 2 is a perspective view of a portion of the insulating core, which forms a detail of my invention. Fig. 3 is a perspective view of a portion of the shell portion of the plug, and illustrates an arrangement for mounting one of the spark points of the plug. Fig. 4 is a perspective view of a spark point, which is adapted to be mounted on the shell portion of the plug. Fig. 5 is a side elevation of the central electrode or terminal plug, which forms a detail of my invention. Fig. 6 is a perspective view of a heat insulating diaphragm. Fig. 7 is a perspective view of a portion of the inner end of the insulating core, and illustrates the method of mounting one of the spark points. Fig. 8 is a perspective view of the spark point shown in Fig. 7, and Fig. 9 is a perspective view of the spark point, bent to lock its mounting nut in place.

Referring to the drawings: The plug illustrated as embodying my invention, consists of an outer shell portion 10, on which a spark point 11 is mounted, an insulating core formed in two parts 12 and 13, and a central 35 electrode or terminal post 14, on which a spark point 15 is mounted.

The shell 10 is bored to two diameters to receive the separate parts 12 and 13 of the core, and is provided with a shoulder formed 40 by the difference in diameter of the bore, on which a heat insulating, preferably mica, diaphragm 16 is mounted, being secured in place by means of the part 12, which is located in the larger portion of the bore. The 45 shell portion is tapped at the upper end of the larger bore to receive a bushing 17, which surrounds the part 12, and is adapted to secure it in place on the shell portion by compressing a packing 18 against a shoulder 50 formed on the part 12, and thereby forcing the part against the diaphragm 16. The packing 18 seals the joint between the shell portion 10 and the insulating core or part 12.

Both the parts 12 and 13 are provided 55 with a longitudinally extending and centrally located cylindrical hole 20, through which the central electrode extends. The electrode 14 is provided with an integrally formed collar 21 and is threaded at each end,

and is mounted in place on the plug by being inserted through the hole 20, provided in the part 12 of the porcelain, so that its collar 21 contacts with the diaphragm 16 and the 5 upper end projects beyond the outer end of the part 12. The electrode 14 is secured in place by means of a slotted nut 22, which is provided with a recess adapted to receive a packing 23. When the packing 23 is forced 10 into place by the nut 22, it seals the joint between the electrode 14 and the porcelain core portion, and the collar 21 is drawn up firmly against the mica diaphragm 16. A lock nut 24 and a terminal nut 25 are provided 15 on the outer end of the electrode 14.

The part 13 of the porcelain core is recessed at 26 to receive the collar 21 and is mounted in place on the plug by being slipped over the projecting lower portion of 20 the electrode 14, and by being secured in place by means of a nut 36, which is secured to the inner end of the electrode.

The electrode is provided on each side adjacent to its inner end with slots 27, which 25 are adapted to receive the spark point 15. The spark point 15 is bifurcated at one end, so as to straddle the posts 14 and to engage the slots 27, and at the other end is provided with a number of points, resembling 30 saw teeth, which cooperate with similar points provided on the spark point 11, to form the spark gap of the plug. After that part 13 is in place on the post 14, the spark point 15 is located on the post and the part 35 13 and the spark point are secured in place by means of the nut 36. The nut 36 is then locked in place by bending down the projecting ends of the bifurcated portion of 40 the spark point, so that they engage one face of the nut and prevent it from turning.

The spark point 11 is provided with a mounting portion, which consists of an integrally formed arch shaped spring, which is adapted to be mounted in an annular 45 slot 29, formed on the inner cylindrical face of the shell portion 10 near its inner end and a vertically extending slot 30 connects with the slot 29, and is adapted to receive and hold in place the shank portion of the 50 spark point. With this construction both the points 11 and 15 are firmly held in place, and their adjustment cannot be disturbed by the vibration of the engine.

When it is necessary to replace the spark 55 point 11, the point is moved so as to compress the arch-shaped spring and withdraw it from the slot 29. The new spark point is mounted on the shell portion 10 by snapping its spring portion in place in the slot. 60 The spark point 15 is removed by first straightening the bifurcated ends, so that the nut 26 may be loosened and then withdrawing it from the slots 27.

When the plug becomes fouled or is short 65 circuited by a deposition of carbon on the

part 13, this part may be removed without disturbing the part 12 by simply removing the nut 36 and the spark point 15.

The saw tooth arrangement of the spark points facilitates the sparking, for the reason that electricity of a high potential seems to accumulate at a point, and with this arrangement there are a number of discharging points.

What I claim is:

1. In a spark plug, a central electrode, an insulating sleeve surrounding said electrode, means for securing the sleeve on the electrode and a spark point mounted on the electrode so as to be non-rotatable relatively 80 thereto and bent to lock said means in place.

2. In a spark plug, a metallic shell, a central electrode, an insulating core divided into two parts and surrounding said electrode, a nut for securing one of said parts to 85 said electrode, and a spark point secured to said electrode by said nut and provided with means for locking said nut.

3. In a spark plug, an insulated electrode, a spark point mounted on the electrode, and 90 non-rotatable relatively thereto, a nut for holding the point in place, and prongs on the spark point capable of being bent into nut-locking engagement with the nut.

4. In a spark plug, a shell, an electrode 95 projecting through the shell and having spark-point engaging slots near its inner end, a bifurcated spark point engaging the slots in the electrode, a nut for securing the point in place and prongs on the point 100 adapted to be bent into nut-locking engagement with said nut.

5. In a spark plug, a shell forming an electrode, a central electrode extending longitudinally through the shell, a sleeve surrounding and carried by the central electrode, means mounted on the electrode for securing the sleeve in place and a spark point carried by the electrode and locking 105 said means in place.

6. In a spark plug, a cylindrical shell forming a terminal of the plug, an insulating sleeve formed in two parts, means for securing the outer part of the sleeve to the shell, a central electrode projecting longitudinally through the outer part of the sleeve and having spark-point receiving slots near its inner end, separate means for securing the electrode to the outer portion of the sleeve, a spark point having flexible 115 prongs formed thereon and engaging the slots formed in the central electrode, and independent means for securing the spark point and the inner part of the sleeve to the electrode, the prongs of said electrode being 120 bent into engagement with said means, for positively locking it in place on the electrode.

7. A spark plug comprising, an insulating sleeve formed in two parts, a shell hav- 130

ing an annular shoulder engaged by the outer part of the sleeve, a bushing surrounding the outer part of the sleeve and locking it to the shell, an electrode projecting through the sleeve and having a shoulder for engaging the inner face of the outer part thereof, a nut for engaging the outer end of the electrode and for securing it to the outer sleeve, a spark point located against the in-

ner end of the sleeve and a nut on the inner end of the electrode for locking the point and the inner part of the sleeve to the electrode.

CHARLES M. CONKLIN.
